DESIGN FOR A COMBINED APPOINTMENT PAD AND CLOCK

Jacob S. Sherman, Chicago, Ill.

Application June 1, 1937, Serial No. 69,634

Term of patent 14 years

To all whom it may concern:

Be it known that I, Jacob S. Sherman, a citizen of the United States and resident of Chicago, in the county of Cook and State of Illinois, have invented a new, original, and ornamental Design for a Combined Appointment Pad and Clock, of which the following is a specification, reference being had to the accompanying drawing, forming a part thereof.

Fig. 1 is a top plan view of a combined appointment pad and clock showing my new design;

Fig. 2 is a side elevational view of the same;

Fig. 3 is a rear elevational view of the same.

I claim:

The ornamental design for a combined appointment pad and clock, substantially as shown.

JACOB S. SHERMAN.
